UNITED STATES PATENT OFFICE.

LOCH F. HUTCHISON, OF NORTHBANCH, KANSAS.

BAG REINFORCEMENT AND HANDLE.

1,233,784.

Specification of Letters Patent.

Patented July 17, 1917.

Application filed April 6, 1916. Serial No. 89,440.

To all whom it may concern:

Be it known that I, LOCH F. HUTCHISON, a citizen of the United States, residing at Northbranch, in the county of Jewell and 5 State of Kansas, have invented certain new and useful Improvements in Bag Reinforcement and Handles, of which the following is a specification.

This invention relates to improvements in 10 fabric receptacles or bags, more particularly to devices of this character employed for conveying rough products, such as dry or pulverized cement and the like, and has for one of its objects to improve the construction and increase the efficiency and utility 15 of devices of this character.

Another object of the invention is to provide a simply constructed attachment which 20 may be applied without structural change to bags of various sizes and to bags constructed of various fabrics and which does not interfere with the ordinary use of the bag.

With these and other objects in view, the 25 invention consists in certain novel features of construction, as hereinafter shown and described and then specifically pointed out in the claims; and in the drawings illustrative of the preferred embodiment of the invention—

30 Figure 1 is a perspective view of one of the improved bags filled and closed;

Fig. 2 is a transverse section on the line 2—2 of Fig. 1;

Fig. 3 is an enlarged sectional detail on the line 3—3 of Fig. 1;

Fig. 4 is an enlarged sectional detail on the line 4—4 of Fig. 1.

Corresponding and like parts are referred to in the following description and indicated 0 in all the views of the drawings by the same reference characters.

The improved device may be arranged in connection with bags of various forms and sizes and to bags employed for various purposes, and does not require any structural change in the bag.

The improved attachment comprises a band represented conventionally at 10 and secured around the interior of the bag, represented conventionally at 11, preferably near the closed lower end and spaced from the open end. Any required number of the bands may be employed but generally two will be sufficient, as shown. The bands will be of any suitable material but will gener-

ally be constructed from the same material as that from which the bag is constructed and rolled longitudinally into a plurality of layers, as represented in Fig. 3, and stitched or otherwise secured at its edges, as indicated at 12, to the body of the bag. The member 10 is designed as a reinforcement to the body of the bag, and extends entirely around the interior of the same, as shown. 60

Attached to the exterior of the bag opposite each of the reinforcing members 10 is a handle or grip member, represented as a whole at 13 and formed of a plurality of layers and of any suitable material. The handles are preferably formed of a suitable 70 number of thicknesses of the material, for instance four, as illustrated in Fig. 3, but any required number of the layers or thicknesses may be employed. When the body of the bag is of sufficiently heavy material a 75 portion of the same material may be employed for the handles, but if heavier or stronger handles are required the latter may be constructed of stronger material as will be obvious. The handle members are 80 secured in any suitable manner, preferably by rivets 14 which pass through all of the thicknesses of the handle members, through the body portion of the bag, and likewise through the several thicknesses of the reinforcing member 10, as shown in Figs. 3 and 4. If found necessary one or both of the heads of the rivets may be reinforced by washers of leather or like material, represented at 15. 85

The strains of the handle members are thus borne by a relatively large portion of the material, the reinforcing members 10 and the handles coating to materially increase the strength and the resisting powers 95 of the bag, and effectually preventing undue strains upon the material of the bag. By this arrangement the strains are distributed over a relatively large portion of the surface of the bag and thereby increasing its 100 durability and resisting powers.

Having thus described the invention, what is claimed as new is:—

1. A device of the class described comprising a receptacle of flexible material, a 105 reinforcing band extending entirely around the interior of the receptacle and attached thereto, a handle bearing at its ends against the exterior of the receptacle with the material of the receptacle between the band and 110

the handle, and fastening devices engaging through the handle ends, the body of the receptacle, and the reinforcing band.

2. A device of the class described comprising a receptacle of flexible material, a reinforcing band extending entirely around the interior of the receptacle and attached thereto, a handle bearing at its ends against the exterior of the receptacle, supplemental reinforcing devices engaging the band opposite the handle ends, and fastening devices engaging through the handle ends, the body of the receptacle, the reinforcing band and the supplemental reinforcing devices.

3. A device of the class described, comprising a receptacle of flexible material including one open end, a reinforcing band extending entirely around the interior of the receptacle and spaced from its open end, said band being attached to the receptacle as by stitching, a handle bearing at its ends against the exterior of the receptacle, with the material of the receptacle between the band and the handle, and fastening devices engaging through the handle, the body of the receptacle and the reinforcing band.

In testimony whereof I affix my signature.
LOCH F. HUTCHISON. [L.S.]
